CHESTER J. MOORE, OF EAST ST. LOUIS, ILLINOIS, ASSIGNOR, BY MESNE ASSIGNMENTS, TO VICTORY MOTORS COMPANY, A CORPORATION OF ILLINOIS.

INTERNAL-COMBUSTION ENGINE.

1,367,825.

Specification of Letters Patent.

Patented Feb. 8, 1921.

Application filed April 2, 1917, Serial No. 159,110. Renewed May 10, 1920. Serial No. 880,844.

To all whom it may concern:

Be it known that I, CHESTER J. MOORE, a citizen of the United States, residing at the city and county of Denver and State of Colorado, have invented certain new and useful Improvements in Internal-Combustion Engines; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 My invention relates to improvements in internal combustion or explosive engines, and my object is to provide a construction of this character which is very compact, economical in cost and exceedingly efficient 20 in operation.

The principal feature of my improved construction is that the pistons which are adapted to reciprocate in each cylinder, are themselves made in the shape of cylinders, 25 and thus I present a construction in which cylinders reciprocate within cylinders. The engine cylinders are arranged in pairs and two rotary valves are located between the cylinders comprising each pair, each of said 30 valves having two passages or ports therein and the said ports adapted to register respectively with ports formed in the casing and communicating with the said cylinders and the two ports of one valve also adapted 35 to register with the manifold, while the two ports of the other valve are also adapted to register with the intake of the engine, and means are provided for rotating both of said valves whereby explosive mixture 40 can be introduced both within the cylinders comprising the pistons and within the cylinders proper of the engine above the heads of the said pistons during one cycle of the engine, and thus explosions will occur at 45 suitably timed intervals above and below the piston heads during each cycle of the said engine.

In carrying out this idea, stationary bulkheads or partitions are located within the 50 piston cylinders, the said bulkheads being mounted in the walls of the engine cylinders by means of pins which extend through elongated slots formed in the said piston cylinders whereby the latter can freely reciprocate and the explosive mixture is com-

pressed and exploded within the pistons between the heads of the latter and upper surfaces of the bulkheads.

By virtue of the above described arrangement enabling me to produce explosions 60 both above and below the piston heads, I obtain twice the number of explosions to each cycle of the engine that is possible to be produced in the engines of ordinary construction, and I thereby greatly increase the 65 power and efficiency of the engine.

Having briefly outlined my improved construction, I will proceed to describe the same in detail, reference being made to the accompanying drawing, in which is illustrated 70 an embodiment thereof. In this drawing:—

Figure 1 is a sectional view of my improved engine taken on the line 1—1 Fig. 2 looking in the direction of the arrow, but 75 showing two sets of cylinders.

Fig. 2 is a sectional view taken on the line 2—2 Fig. 1 looking in the direction of the arrow.

Fig. 3 is a view taken on the line 3—3 80 Fig. 1 looking in the direction of the arrow.

Fig. 4 is a section taken on the line 4—4 Fig. 2 looking in the direction of the arrow.

Fig. 5 is a detail sectional view of the cylinder comprising the piston.

Fig. 6 is a detail view of one of the bulkheads which I employ in my improved construction.

Fig. 7 is a sectional view taken on the line 7—7 Fig. 2 looking in the direction of 90 the arrow.

The same reference characters indicate the same parts in all the views.

Let the numeral 5 designate a crank case in which is journaled a crank shaft 6. Near 95 the left-hand end of the case (referring to Fig. 1) a gear wheel 7 is secured upon the crank shaft and adapted to mesh with a larger gear wheel 8 loosely mounted upon a journal 9, the diameter of the gear wheel 8 100 being twice that of the gear wheel 7. Also loosely mounted upon the journal 9 and connected with the gear wheel 8 as disclosed at 10 is another gear wheel 12 somewhat smaller in diameter than the said gear 105 wheel 8, but approximately twice as thick as the latter. This gear wheel 12 is adapted to mesh with two gear wheels 13 and 14 rigidly mounted upon shafts 15 and 16 respectively which are journaled in the crank cas- 110

ing 5 and the three gear wheels 12, 13 and 14 are of the same diameter.

Mounted upon the gear casing 5 is an engine casing 17 having four cylinders bored 5 therein, the said cylinders being arranged in groups of two each, the cylinders of the group to the left (referring to Fig. 1) being designated by the numerals 18 and 19 and the cylinders of the group to the right being 10 designated by the numerals 20 and 21, the top walls of all of the said cylinders being inclined to facilitate the compression of explosive mixture. This engine casing is provided with the usual water jacket 22 secured 15 thereto as shown at 23.

Adapted to reciprocate in each of the engine cylinders, is a cylinder shaped piston 24 composed of a sleeve 25 and upper and lower heads 26 and 27 respectively (see Fig. 20 5), the lower head 27 being provided with spaced perforated ears 28 adapted to be pivotally connected with the upper extremity of a pitman 29 by means of a pin 30. The lower extremity of this pitman 29 is pivotally connected at 31 with crank arms 32 secured to the crank shaft 6, the connections 25 between the two pitmen of each pair of cylinders and the said crank shaft 6 being 180° apart.

30 Located in each engine cylinder and within the sleeve 25 of the piston 24 is a cylindrical bulkhead or elongated partition 33 (see Figs. 1 and 6) which is stationary, the said bulkhead being supported by the wall 35 of the engine cylinder by means of a pin 34 which is passed through the bulkhead to one side of a perpendicular plane passed through the center of the latter and whose extremities enter perforations 35 formed in 40 the said cylinder wall. The said pin 34 also extends through two elongated slots 36 formed in the sleeve 25 of the piston whereby the latter can freely reciprocate within the engine cylinder. Also the upper surface 45 of each bulkhead is inclined as disclosed at 37 to facilitate compression of the explosive mixture upon the downward stroke of the piston. The sleeve 25 of the piston is further provided with two elongated slots 38 50 and 39 which are adapted to be continuously in register with ports 40 and 41 respectively formed in the engine casing, the said ports communicating respectively with openings 42 and 43 which are also formed in 55 the engine casing and in which openings are located relatively long cylindrical valves 44 and 45 respectively adapted to rotate therein. The lower extremities of these valves 44 and 45 bear upon shoulders 46 of the 60 engine casing and are provided with packing rings 47 to form a fluid-tight connection. The upper extremities of the said valves enter recesses formed in the top of the casing and are provided with flanges 48 which engage the bottoms of the said recesses. These

recesses are closed by screw caps 49 whose under-surfaces are recessed as shown at 50 to receive balls 51 and between which and the tops of the valves 44 and 45 which are also recessed, are located coiled springs 52 70 whereby the said valves are placed under tension.

In the further description of my improved construction, the valve mechanism will be described with reference to one cylinder only, 75 viz., 18, inasmuch as the valves between each pair of cylinders operate in the same manner with respect to both of said cylinders, and the openings in which the valves are located, are in communication with the cylinders arranged upon opposite sides thereof by means of ports formed in the casing opposite each other.

Referring to Fig. 7, the valve 44 is provided with an upper port 53 which is adapted 85 to form communication between the intake 54 of the engine and a port 55 formed in the casing which port establishes communication between the upper extremity of the cylinder 18 and the opening 42 in which the 90 said valve 44 is located. The valve 44 is also provided with a lower port 56 adapted to form communication between the intake 54 and the port 40 formed in the casing between the cylinder 18 and the said opening 95 42 in which the valve 44 is located, this port 40 also being at all times in communication with the interior of the piston 24 through the medium of the elongated slot 38 in the latter.

The valve 45 is provided with an upper port 57 which is adapted to form communication between the exhaust 58 of the engine and a port 59 formed in the casing between the upper extremity of the cylinder 18 and the opening 43 in which the said valve 45 is located. The valve 45 is also provided with a lower port 60 adapted to form communication between the exhaust 58 and the port 41 formed in the casing between the cylinder 18 and the opening 43 in which the said valve 45 is located. The port 41 is also at 105 all times in communication with the interior of the cylindrical shaped piston 24 by means of the elongated slot 39 in the latter. Furthermore, a spark plug 61 is located in the port 40 and a spark plug 62 is located in the port 55. 115

Connected with the lower extremity of each valve 44 and 45 is a rod or stem 63 120 which extends through the lower portion of the engine casing and projects into the crank case 5, the lower extremity of the said rod having secured thereon a bevel gear 64 adapted to mesh with the similar bevel gear 125 65 secured upon the shafts 15 and 16, there being two bevel gears 65 upon each of said shafts to correspond to the four valves. In view of this connection between the valves 44 and 45 and the shafts 15 and 16 upon 130

which the gear wheels 13 and 14 are respectively mounted, the said valves will be given a half turn for each complete revolution of the crank shaft 6 since the diameter 5 of the gear wheel 7 secured upon the latter is only one-half that of the gear 8, while gear wheel 12 which is secured to the said gear wheel 8 and adapted to mesh with the gear wheels 13 and 14 is of the same diameter as the latter. It also follows that for each half revolution of the crank shaft 6 a quarter turn will be imparted to the valves 44 and 45.

In view of the above description, the operation of my improved construction will be readily understood, and in describing this operation, reference is made particularly to Fig. 7 as this is the only figure in which the exact relation of both valves to a single cylinder is disclosed, and it is believed that such description will be sufficient, since as before mentioned, the operation of the valves is the same with respect to both of the cylinders between which they are located.

In the first place, it will be assumed that an explosion has just taken place within the piston 24 between the bulkhead 33 and the piston head 26 whereby the said piston is forced to its upward limit of movement, and it will also be assumed that upon this stroke of the said piston, gas is compressed in the upper portion of the engine cylinder 18 above the head 26 of the piston. This position of the piston is disclosed in Fig. 7 and it will be noticed that the port 60 of the valve 45 is in register with the port 41 of the casing and the exhaust 58, all other communication with the engine cylinder and the interior of the piston being cut off. The charge of explosive mixture above the piston head 26 will then be ignited by the spark plug 62 which will force the piston downwardly and during this stroke the interior 40 of the latter between the bulkhead 33 and the said piston head 26, will be scavenged by way of the port 60 of the valve 45. By the time the piston has reached its lowermost limit of movement, a quarter of a turn 45 to the right will have been imparted to each valve which will throw the port 60 of the valve 45 out of register and bring the port 57 of said valve into register with the port 59 in the casing and exhaust 58. Also 50 the port 56 of the valve 44 will be brought into register with the intake 54 and the port 40 in the casing. By virtue of this fact during the upward stroke of the piston, explosive mixture will be drawn into the latter between the piston head 26 and the bulkhead 33 by way of port 56 of the valve 44 and the cylinder 18 above the piston head 26 will be scavenged by way of the port 57 which is in register with the exhaust 58. Another quarter of a turn has

now been imparted to the valves 44 and 45 whereupon the port 53 of the valve 44 is brought into register with the intake 54 and port 55 of the casing, the other ports of both valves being now out of register. Thus 50 during the downward stroke of the piston, the explosive mixture within the latter between the head 26 thereof and the bulkhead 33 will be compressed, while a fresh charge 55 of explosive mixture is being drawn into the cylinder 18 above the said piston head 26 by way of the port 53 of the valve 44. When the piston has reached its lowermost position, the ports of both valves will be out of register since the said valves have been 60 given another quarter turn and the charge 65 of compressed explosive mixture within the piston will be ignited by the spark plug 61 whereby the piston will be forced upwardly and the mixture within the cylinder 18 70 above the piston head 26 will be compressed. By this time the valves will be again rotated to the position disclosed in Fig. 7 wherein the port 60 of the valve 45 is in 75 register with the interior of the piston and the exhaust 58 and the charge of mixture 80 in the cylinder 18 above the piston head is compressed and ready for ignition, when the aforesaid operation is repeated. It will, of course, be understood that the same 85 operation takes place within each cylinder, but the steps of the operation take place at different intervals in each of said cylinders, and thus it will be readily seen that I obtain twice the number of explosions in each 90 cylinder during one cycle of the engine that is possible to produce in an engine of the ordinary construction.

Having thus described my invention, what I claim is:

105

1. In an internal combustion engine the combination with a pair of cylinders provided with ports, a piston in each cylinder in the form of a sleeve, passages through said sleeves whereby the interior of each piston is in communication with certain of said ports, a pair of valves rotatably mounted adjacent said cylinders, each valve having passages therein adapted for communication with each cylinder through said 110 ports.

2. In an internal combustion engine the combination with a pair of cylinders provided with ports, a piston in each cylinder in the form of a sleeve, passages through 115 said sleeves whereby the interior of each piston is in communication with certain of said ports, a pair of valves rotatably mounted adjacent said cylinders, each valve having passages therein adapted for communication with each cylinder through said ports, the passages in each of said valves being arranged at right angles to one another.

3. In an internal combustion engine the 120

combination with a pair of cylinders provided with ports, a piston in each cylinder in the form of a sleeve, passages through said sleeves whereby the interior of each 5 piston is in communication with certain of said ports, a pair of valves rotatably mounted adjacent said cylinders, each valve having passages therein adapted for communication with each cylinder through said 10 ports, and a stationary partition within each of said pistons.

4. In an internal combustion engine the combination of a cylinder provided with ports, a piston comprising a sleeve having upper and lower heads adapted to reciprocate within said cylinder, the sleeve of the 15 piston being provided with slots continually in register with certain of the ports of the cylinder, and valves mounted adjacent the latter provided with ports adapted to register respectively with the ports of the said cylinder for the purpose set forth and a stationary partition mounted within said piston.

25 5. In an internal combustion engine the combination of a cylinder provided with ports, a piston comprising a sleeve having upper and lower heads adapted to register within said cylinder, the sleeve of the piston 30 being provided with slots continually in register with certain of the ports of the cylinder, a bulkhead located within said sleeve, a pin passed through the said bulkhead and its extremities extending through the slots 35 in the sleeve and entering perforations formed in the wall of the cylinder, and valves rotatably mounted adjacent the latter and provided with ports adapted to register respectively with the ports of the cylinder 40 for the purpose set forth.

6. In an internal combustion engine the combination with the manifold and exhaust, of a cylinder provided with ports, a piston in the form of a cylinder adapted to reciprocate within said cylinder, a partition located 45 within the piston, but attached to the engine cylinder, and two valves rotatably mounted adjacent the latter provided with ports adapted to register respectively with the 50 ports of the engine cylinder and the ports of one valve also adapted to register with the manifold, while the ports of the other valve are also adapted to register with the exhaust of the engine.

55 7. In an internal combustion engine the combination with the manifold and exhaust, of a cylinder provided with four ports, a piston in the form of a cylinder adapted to reciprocate in the engine cylinder, the interior 60 of said piston cylinder being constantly in communication with two of said ports, a partition located within the piston, but attached to the engine cylinder, and two valves 65 rotatably mounted adjacent the latter and each valve provided with two ports, said

ports adapted to register respectively with the four ports of the engine cylinder and the two ports of one valve also adapted to register with the manifold, while the two ports of the other valve are also adapted to register with the exhaust of the engine. 70

8. In an internal combustion engine the combination with the crank shaft, manifold and exhaust, of a cylinder provided with four ports, a piston in the form of a cylinder 75 connected with the said crank shaft and adapted to reciprocate in the engine cylinder, the interior of said piston cylinder being constantly in communication with certain of said ports, a partition located within the piston, but attached to the engine cylinder, two cylindrical valves rotatably mounted adjacent the latter and each valve provided with two ports, said ports adapted to register respectively with the ports of the 80 engine cylinder and the two ports of one valve also adapted to register with the manifold, while the two ports of the other valve are also adapted to register with the exhaust of the engine, and means for imparting a quarter of a turn to each of said 85 rotary valves for each half revolution of the crank shaft of the engine for the purpose set forth.

9. In an internal combustion engine the combination with the crank shaft, manifold and exhaust of a pair of cylinders each provided with four ports, pistons in the form of cylinders connected with the said crank shaft and adapted to reciprocate in the engine cylinders, the interior of said piston cylinders being constantly in communication with certain of said ports of the respective engine cylinder, partitions located within the pistons, but attached to the engine 95 cylinders, two cylindrical valves rotatably mounted between the latter, and each valve provided with two ports, said ports adapted to register respectively with the oppositely disposed ports of the engine cylinders and the two ports of one valve also adapted to register with the manifold, while the two ports of the other valve are also adapted to register with the exhaust of the engine, and means for imparting a quarter of a turn to 100 each of said rotary valves for each half revolution of the crank shaft of the engine for the purpose set forth. 105

10. An internal combustion engine including a cylinder having ports, a piston in the form of a cylinder adapted to reciprocate in said engine cylinder, and a partition located within the piston, but attached to the wall of the engine cylinder the piston having a slot continually in register with certain of the cylinder ports. 110

11. An internal combustion engine including a cylinder having ports, a piston adapted to reciprocate therein, said piston comprising a sleeve closed at one end, and a 115

partition located within the said sleeve, but supported by the cylinder the piston having a slot continually in register with certain of the cylinder ports.

- 5 12. An internal combustion engine including a cylinder having ports, a piston adapted to reciprocate therein, said piston comprising a sleeve closed at one end and having slots formed therein, a partition located within the said sleeve, and means secured to the said partition and extending

through the slots in the sleeve and adapted to enter perforations formed in the wall of the cylinder for the purpose set forth, said piston having other slots continually in register with the cylinder ports. 15

In testimony whereof I affix my signature, in presence of two witnesses.
